(57) **CLAIM**

The ornamental design for a pair of combined gloves/mittens, as shown and described.

DESCRIPTION

FIG. 1 is a front elevation view of a right-hand combined glove/mitten, with the pocket flap in an open position, and the mitten flap secured.

FIG. 2 is a rear elevation view of the embodiment of FIG. 1. FIG. 3 is a front elevation view of the embodiment of FIG. 1 with the pocket flap in a closed position, and the mitten flap disengaged and folded behind the finger stalls of the glove. FIG. 4 is a rear elevation view of the embodiment of FIG. 1, showing the mitten portion folded back.

FIG. 5 is a further rear elevation view of the embodiment of FIG. 1 wherein the mitten portion shown in FIG. 4 has been folded back a second time.

FIG. 6 is a front elevation view of a left-hand combined glove/mitten, with the pocket flap in an open position, and the mitten flap secured.

FIG. 7 is a rear elevation view of the embodiment of FIG. 6. FIG. 8 is a front elevation view of the embodiment of FIG. 6 with the pocket flap in a closed position, and the mitten flap disengaged and folded behind the finger stalls of the glove. FIG. 9 is a front perspective view showing the claimed design worn with the mitten flaps engaged; and,

FIG. 10 is a perspective view showing the claimed design worn with the mitten flaps disengaged and folded back from the finger stalls of the glove.

The pair of combined gloves/mittens is shown in FIGS. 1-8 separately for ease of illustration.

The darker, patterned areas are hook-and-loop fasteners. The broken lines shown on the surfaces of the claimed design are stitching and form a part of the claimed design. The partial human figure shown in broken lines illustrates the design as it appears when worn, and forms no part of the claim.
